UNITED STATES PATENT OFFICE.

GEORGE C. BEIDLER, OF OKLAHOMA, OKLAHOMA.

DEVELOPING APPARATUS.

1,160,240.

Specification of Letters Patent.

Patented Nov. 16, 1915.

Application filed March 23, 1907. Serial No. 364,016.

To all whom it may concern:

Be it known that I, GEORGE C. BEIDLER, citizen of the United States of America, residing at Oklahoma city, in the county of Oklahoma and State of Oklahoma, have invented certain new and useful Improvements in Developing Apparatus, of which the following is a specification.

This invention relates to photographing and developing apparatus and particularly to means for exposing a sensitized film to light and for conducting the same through a series of tanks or compartments for the purpose of developing and fixing the exposed film.

The invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which—

Figure 1 illustrates a top plan view of an apparatus embodying the invention, a portion of the top being removed to show the parts thereunder in plan; and Fig. 2 illustrates a vertical longitudinal sectional view thereof.

In these drawings A denotes a magazine for containing a roll of film and B a part of the casing through which film is drawn by the rollers C, C, and D denotes the main body of the casing of which the magazine A and chamber B are parts, as shown herein, although the inclosure or casing may be of any appropriate construction.

Within the casing, I mount two drums E and F so that they are free to rotate and I further provide receptacles G and H in which the peripheries of the drums extend. It is intended that the said receptacles G and H shall contain fluid which will act on the coated surface of the film and in practice, it is usual to place developing fluid in the receptacle G and fixing fluid in the receptacle H, so that exposed film is first developed and then fixed.

A pulley I is mounted to rotate between the drums E and F, whereas a pulley J is mounted to rotate near one end of the casing and a pulley K is mounted to rotate near the opposite end of the casing and the said pulleys and the drums have conveying mem-

bers R consisting of tapes, bands, cords, chains or other flexible devices capable of traveling in a circuitous route around the pulleys and in contact with the peripheries of the drums. Pulleys L and M are also rotatably mounted in the casing and engage the flexible members R constituting guides therefor, whereas there is a bracket O externally of the casing in which a pulley N is mounted and the flexible members travel in contact with the pulley N. As a means for holding the flexible members taut, weights o are hung from pulleys o', and these weights hang below the flexible members and pull them downwardly so that a uniform tension is maintained on the several flexible members.

Brushes 1 and 2 are rotatably mounted so as to contact respectively with the drums E and F, the said brushes being designed for the purpose of dislodging films from the drum E and F should such films, by reason of their moistened condition, have a tendency to remain on the drums after the films have traveled beyond the pulley I or the pulley K. The shaft of the brush 1 has a pulley 1^a and the shaft of the brush 2 has a pulley 2^a, and these pulleys are connected by a belt 3^a. The pulley P has a pulley a with a pulley a' extending from it to a pulley a' on the shaft of the brush. The shaft of the pulley P is rotated by a crank S and hence the pulley a on the shaft of the pulley P communicates motion to the brushes through the pulleys 1^a and 2^a and the belt 3^a. A pulley a² is furthermore mounted on the shaft of the pulley P and a belt Q from said pulley engages the pulley a³ on the shaft of the pulley J, thus when the pulley P is rotated, the pulley J is positively driven.

The shaft of the pulley P has a gear wheel T and this gear wheel meshes with a gear wheel T' on one of the rollers C so that the rollers are driven to feed the film.

As a means for arresting the crank shaft S at each rotation, I provide the lever V having an arm v with a lug v' in the path of travel of the said crank. The gear wheels T and T' are in such relation that the feeding rollers will be driven to draw a predetermined length of film, while the crank handle has been turned once, thus the operator may know when a given length of film has been drawn from the magazine so that the said given length may be properly ex-

posed to light. By operating the handle Y, the lug v' may move from engagement with the crank and the said crank may then be free to turn for further operation of the film drawing means and for the operation of the flexible members constituting the conveyers so that film may be carried through the receptacles by the drums and conveyers. The pulleys I and K are driven from the pulley P through the medium of two belts E², E² and pulleys, one of which E³ is on the shaft of the pulley I and the other of which E⁴ is on the shaft of the pulley K. It follows from what has been said that rotation of the crank S to turn the pulley P results in driving the pulleys I, J, and K, and as the flexible members R engage said pulleys motion is communicated to the flexible members and the flexible members carry the film with those portions of the drums that are in the fluid and serve to effect the developing and fixing of the film, it being shown in the drawing that the said film, identified in the drawing by the reference character R', is drawn from the magazine by the rollers C, C.

I claim—

1. In a machine relating to photography, a casing closed against actinic light in communication with means for containing a supply of film adapted to be photographically treated, means for delivering the film after exposure from the means for containing a supply thereof to the said casing, a receptacle within the casing, a drum in the casing rotatably supported with its periphery extending into the receptacle, traveling members in the casing adapted to hold the film on the drum while the said drum is ro-

tated, and means for rotating the drum and operating the traveling members and the means for delivering the film to the casing in unison.

2. In a machine relating to photography, a magazine for containing a roll of film, means for delivering and cutting the portion of the film exposed from the remainder thereof, receptacles for containing liquid, drums mounted to rotate in the receptacles, a pulley at the rear of the drums, a pulley at the front of the drums, a pulley between the drums, conveyers running over the pulleys and contacting with the drums, and weights on the conveyers for regulating the tension thereof.

3. In a machine relating to photography, means for containing a supply of film, a casing in communication with the means for containing a supply of film, receptacles within the casing, drums mounted with their peripheries in the receptacles, means for feeding film from the means for containing the film to the casing, pulleys between the drums, traveling members in the casing adapted to coact with the peripheries of the drums, for holding the films in contact with the drums, the said traveling members operating over the pulleys and carrying the film from one of the drums to the other, and means for operating the rotatable parts of the device simultaneously.

In testimony whereof I affix my signature in the presence of two witnesses this 15th day of March, 1907.

GEORGE C. BEIDLER.
